**LAUNDRY MACHINE AND A DUMP VALVE
THEREFOR**

William Courtney Files, Cincinnati, Ohio, assignor to
McGraw-Edison Company, Milwaukee, Wis., a corpora-
tion of Delaware

Filed Apr. 28, 1964, Ser. No. 363,148
12 Claims. (Cl. 68—208)

This invention relates to dump valves and, more par-
ticularly, to dump valves for discharging fluid from the
tub of a horizontal washing machine.

One type of laundry appliance is provided with a
washer-extractor cylinder which is rotated about a hori-
zontal axis. The work is washed in such devices at a
relatively low tumbling speed and, thereafter, the rota-
tional speed of the cylinder is increased to centrifugally
extract liquid from the load through perforations in the
cylinder. When the cylinder is accelerated toward the
centrifugal extraction speed, there is a large amount of
liquid thrown out of the saturated load of fabric through
the perforated cylinder wall. The bulk of the extracted
liquid is discharged within a relatively short period of
time, after which the quantity of extracted liquid tapers
off. The liquid thus forcefully ejected into the space
between the cylinder and the encircling tub tends to
cumulate and act as a drag on the rapidly rotating cylinder,
unless it can be cleared out of the tub quickly. One prior art means for rapidly discharging the extracted fluid
has been to employ a dump valve which extends for a
substantial portion of the cylinder length. The latter
employs hollow rubber valve elements which close the
valve opening upon being inflated. This has not been
wholly satisfactory, however, because the rubber valve
elements tend to deteriorate with age and use and are
costly to replace.

It is an object of the invention to provide a new and
improved dump valve for rapidly discharging the fluid
from a horizontal washer-extractor.

A further object of the invention is to provide a laun-
dry appliance dump valve which is simple, low in cost and
easy to maintain.

Another object of the invention is to provide the dump
valve for the tub of a laundry appliance wherein a tub
discharge valve opening extends for a substantial portion
of the tub length and wherein an elongate rigid member
is operative to move sealing means into and out of en-
gagement with the periphery of the valve opening. A
more specific object of the invention is to provide such
a dump valve assembly wherein each of the opposite
ends of the elongate rigid member is carried by motive
means for movement into and out of engagement with
the valve opening.

These and other objects and advantages of the instant
invention will become more apparent from the detailed
description thereof taken with the accompanying drawing
in which:

FIG. 1 illustrates a washing machine incorporating the
instant invention;

FIG. 2 is a view taken along lines 2—2 of FIG. 1;

FIG. 3 is a view taken along lines 3—3 of FIG. 2;

FIG. 4 is a view taken along lines 4—4 of FIG. 2;

FIG. 5 illustrates the dump valve according to the in-
stant invention in its open position; and

2

FIG. 6 schematically illustrates means for moving the
dump valve to its alternate positions.

Referring to the drawings in greater detail, FIG. 1
shows a washer-extractor 10 having a perforated washer-
extractor cylinder 11 which is mounted for rotation about
a horizontal axis by means which are not shown but
which are well known in the art. A tub 12 surrounds
the cylinder 11 for holding the fluid during a washing
operation and for receiving fluid discharged from the
cylinder 11 during the extracting operation. End walls
13 close the tub 12 and the entire assembly is surrounded
by an outer casing 14.

A pair of end to end drain assemblies 15 open into
suitable openings 16 in the bottom of the tub 12. The
drain assemblies 15 are identical and, accordingly, only
one will be discussed in detail, for the sake of brevity.
While it will be appreciated that the drain assembly 15
may take any convenient form, in the illustrated embodiment
it is shown to include an inclined floor plate 17
which is affixed at one end to one side of the periphery
of the opening 16 and slants away from said opening in
a direction tangent to the tub 12 and in the direction of
cylinder rotation which in FIG. 1 is counterclockwise.
An end wall and valve opening for the drain assembly 15
is formed at the lower end of the floor plate 17, as seen
in FIGS. 2, 4 and 5, by a channel member 18 suitably
affixed at its upper end to the underside of the tub 12 and
an angle member 19 suitably affixed to the lower edge
of floor plate 17. The lower surface 20 of the channel
member 18 and the upper surface 21 of the angle mem-
ber 19, which are spaced apart from each other along
their entire lengths, form an elongate rectangular dis-
charge opening 22 for the drain assembly 15 facing in
the direction of cylinder rotation. A pair of end plates
24 provide sidewalls for the drain assembly 15 and are
shaped to register with the side marginal edges of the
tub opening 16 and the corresponding ends of the floor
plate 17, the channel member 18 and the angle mem-
ber 19.

While two drain assemblies 15 are shown, it will be
understood that a single correspondingly longer assembly
may also be employed, the instant construction being
preferable when the cylinder 11 is divided by a transverse
panel, not shown.

A dump valve closure assembly 30, according to the
instant invention, is provided for closing the discharge
port openings 22. The closure assembly 30 includes an
elongate, relatively rigid, metallic bar 32 which according
to the illustrated embodiment is hollow and rectangular
in cross-section, although it will be appreciated that it
may take any suitable form.

A pair of sealing strips 33 are affixed to the face of
the bar 32 opposite the discharge port openings 22 in
any suitable manner such as by cement and a plurality of
screws 34. It will be appreciated that the strips 32 are
at least co-extensive with and preferably slightly larger
than their associated openings 22 in the drain assemblies
15 so that when the bar 32 is in its closed position shown
in FIG. 4, the openings 22 will be sealed.

While it will be understood by those skilled in the art
that the bar 32 may be displaced between its closed posi-
tion shown in FIG. 4 and its open position shown in FIG.
5 by any suitable means, a pair of air motors 35 are pro-
vided for this purpose in the illustrated embodiment.
Each of the air motors 35 includes a cylinder 36 and a

piston 37 which carries a piston rod 38. The air motors 35 are preferably of the type where piston rod 38 extends through the opposite ends of the cylinder 36 through sealing bushings 40 so that the forward end of the rod 38 may be secured to the bar 32 while the other end provides added support and prevents binding due to the weight of bar 32.

Each of the opposite ends of the bar 32 extends outwardly through openings 42 formed in the end walls 13 for engagement with the forward end of its associated piston rod 38. The air motor cylinders 36 are affixed by L-shaped brackets 43 to the outer surface of its associated end wall 13 and adjacent the opening 42 formed therein.

The forward portion of the piston rod 38 is threaded and fits with registering clearance openings 46 formed in the opposite faces of the bar 32. Nuts 48, which are threadably received on the forward end of the rod 38, adjustably secure the bar 32 to the rod 38 and position the bar relative to the opening 22 in the drain assembly 15. A pair of thick rubber washers 49 are provided between the bar 32 and the nuts 48 so that the bar will be self-aligning with the opening 22 when the sealing strip 33 is moved into sealing contact with the edge of the opening 22. In addition, flat metal washers 50 may also be provided between the nuts 48 and the rubber washers 49.

The illustrated air motors 35 are preferably of the double-acting type and their corresponding ends are connected in parallel to each other and to a suitable valve 52 by conduits 53 and 54 to provide simultaneous operation. The valve 52 is of a type which selectively admits air to either conduit while exhausting the other to atmosphere. It can be seen, therefore, that operation of valve 52 in a first sense will admit air to the front inlet of the valve cylinders 36 through conduit 54 so that the bar 32 will be moved away from the discharge ports 22 while operation of the valve 52 in an opposite sense will admit pressure to the back ends of the cylinders 36 through conduit 53 to move bar 32 toward the discharge ports 22.

The air motors 35 will be of proper dimensions and so positioned that when drain closure is effected by admitting air to the forward ends of the cylinders 37 through conduit 53, there will be some clearance between the pistons 37 and the end of the cylinders 36. On the other hand, when the pistons 37 reach the limit of their movement in the opposite direction, the bar 32 will be at the required distance from the openings 22 in the drain assemblies 15 as shown in FIG. 5. The threaded mountings allow some adjustment in this respect.

During normal operation of the machine, the bar 32 is in its position shown in FIG. 4, wherein the sealing strip 33 is against the peripheral edge of the openings 22 and the tub 12 is sealed. When the extraction operation is to be performed, pressure is applied to the back of the cylinders 36 through conduit 54 and the bar 32 is moved away from the openings 22 to its position shown in FIG. 5 so that the extracted fluid may discharge through the drain assemblies 15, against the face of the bar 32 and down through a floor drain which is not shown but is well known in the art.

While only a single embodiment of the invention has been shown and described, it is not intended to be limited thereby but only by the scope of the appended claims.

I claim:

1. In a laundry appliance having a perforated rotatable work treating enclosure, tub means surrounding said enclosure, an opening in said tub means and extending for a substantial portion of the length thereof, closure means for said opening including an elongate member disposed in a substantially parallel relation relative thereto, elongate sealing means on said elongate member and opposed to said opening, said sealing means being of a size to seal said opening first and second motive means each including a first stationary part coupled to receive an actuating quantity and a second part disposed within said first part and movable in response to said actuating

quantity, stem means extending from each of said second parts, and means for adjustably connecting each of said stem means to said elongate member, said motive means being operative for moving said elongate member and sealing means into and out of sealing engagement with said opening upon the application of an actuating quantity to each of said first parts.

2. In a laundry appliance having a perforated rotatable work treating cylinder, tub means surrounding said cylinder, drain means opening into said tub means and having a discharge opening extending for a substantial portion of the length thereof, closure means for said opening including a rigid elongate member having a surface disposed in opposed relation relative to said opening, elongate sealing means on said surface, said sealing means being of a size to seal said opening, and a pair of motive means each having a coupling member disposed substantially normal to the axis of said elongate member, adjustable means for adjustably coupling each of said coupling members adjacent one end of said elongate member, said motive means being operable to move said elongate member and sealing means into and out of engagement with said opening, and resilient means disposed between said adjustable means and said elongate member so that said elongate sealing means may be snugly seated against said opening.

3. In a laundry appliance having a perforated work treating cylinder mounted for rotation about a horizontal axis, tub means surrounding said cylinder, drain means opening into the bottom of said tub means and having a discharge opening extending for a substantial portion of the length thereof; closure means for said opening including an elongate bar, said bar having one surface at least as large as said opening and disposed in opposed relation relative thereto, elongate sealing means on said surface, said sealing means being of a size to seal said opening, and a pair of fluid motor means each including a cylinder and a piston disposed within said cylinder, stem means extending from each of said pistons and arranged generally parallel with each other, and means for adjustably connecting one of said stem means adjacent each end of said bar, said fluid motors being operative to move said bar and sealing means into and out of sealing engagement with said opening.

4. In a laundry appliance having a perforated work treating cylinder mounted for rotation about a horizontal axis, tub means surrounding said cylinder, drain means opening into said tub means and having a portion substantially tangent to said cylinder and extending in the direction of rotation thereof, said drain means having an opening at the remote end of said portion and extending for a substantial portion of the length of tub means, closure means for said opening including an elongate bar being at least as large as said opening and disposed in opposed relation relative thereto, elongate resilient sealing means mounted on said bar and opposed to said opening, said sealing means being of a size to seal said opening, a pair of motive means each including a first stationary part coupled to receive an actuating quantity and a second part disposed within said first part and movable in response to said quantity, stem means extending from each of said second parts and arranged generally parallel with each other, and means for adjustably connecting each of said stem means in spaced apart relation to said bar, said motive means being operative for moving said bar and sealing means into and out of engagement with said opening upon the application of an actuating quantity to each of said first parts.

5. In a laundry appliance having a perforated work treating cylinder mounted for rotation about a horizontal axis, tub means surrounding said cylinder, drain means opening into the bottom of said tub means and having a portion substantially tangent to said cylinder and extending in the direction of rotation thereof, said drain means having an opening at the remote end of said portion and extending for a substantial portion of the length of said

tub means, closure means for said opening including a hollow elongate bar, said bar being rectangular in cross-section and having one surface at least as large as said opening and disposed in opposed relation relative thereto, resilient sealing means affixed to said surface and being of a size to seal said opening, and a pair of fluid motor means each having a coupling member disposed substantially normal to the axis of said bar, adjustable means for adjustably coupling each of said coupling members to one end of said bar, said fluid motors being operable to move said bar and sealing means into and out of engagement with said opening, and resilient means disposed between said adjustable means and said bar so that said resilient sealing means may be snugly seated against said opening.

6. In a laundry appliance having a perforated work treating cylinder mounted for rotation about a horizontal axis, tub means surrounding said cylinder, drain means opening into the lower end of said tub means and having an opening extending for a substantial portion of the length of said tub means, closure means for said opening including an elongate member having a surface at least as large as said opening and disposed in opposed relation relative thereto, elongate sealing means affixed to said surface and mounted on said member in opposed relation to said opening, said sealing means being of a size to seal said opening, a pair of motor means each having a first part coupled to receive an actuating quantity and a second part disposed in operative association with said first part and movable in response to said quantity, stem means extending from each of said second parts and being substantially normal to the axis of said elongate member, means for adjustably connecting each of said stem means to one end of said elongate member, said motor means being operable to move said elongate member and sealing means into and out of engagement with said opening.

7. In a laundry appliance having a perforated work treating cylinder mounted for rotation about a horizontal axis, tub means surrounding said cylinder, drain means opening into the lower end of said tub means and having an opening extending for a substantial portion of the length of said tub means, closure means for said opening including an elongate bar having a surface at least as large as said opening and disposed in opposed relation relative thereto, elongate resilient sealing means affixed to said surface and mounted on said bar in opposed relation to said opening, said sealing means being of a size to seal said opening, a pair of fluid motor means each having a coupling member disposed substantially normal to the axis of said bar, nut means for adjustably coupling each of said coupling members to one end of said bar, said fluid motor means being operable to move said bar and sealing means into and out of engagement with said opening, and resilient means disposed between said nut means and said bar so that said resilient sealing means may be snugly seated against said opening.

8. In a laundry appliance having a perforated work treating cylinder mounted for rotation about a horizontal axis, tub means surrounding said cylinder, elongate drain means opening into the lower end of said tub means and having a portion substantially tangent to said cylinder and extending in the direction of rotation thereof, said drain means having an elongate opening at the remote end of said portion and extending for a substantial portion of the length of said tub means, closure means for said opening including a hollow elongate bar, said bar being rectangular in cross-section and having one surface at least as large as said opening and disposed in opposed relation relative thereto, resilient sealing means affixed to said surface in opposed relation to said opening, said sealing means being of a size to seal said opening, a pair of fluid motor means each having a coupling member disposed substantially normal to the axis of said bar, nut means for adjustably coupling each of said coupling members to one end of said bar, said fluid motor means being operable

to move said bar and sealing means into and out of engagement with said opening, and resilient washer means disposed between said nut means and said bar so that said resilient sealing means may be snugly seated against said opening.

9. In a laundry appliance having a perforated work treating cylinder mounted for rotation about a horizontal axis, tub means surrounding said cylinder, a pair of elongate drain means opening into the lower end of said tub means and each having a portion substantially tangent to said cylinder and extending in the direction of rotation thereof, said drain means being disposed in endwise relation and each having an opening at the remote end of said portion and extending for a substantial portion of the length of said tub means, closure means for said openings including a hollow elongate bar, said bar being rectangular in cross-section and having one surface at least as large as said openings and disposed in opposed relation relative thereto, a pair of resilient sealing members affixed to said surface and each disposed in opposed relation to one of said openings, each of said sealing means being of a size to seal its respective opening, a pair of fluid motor means each having a coupling member disposed substantially normal to the axis of said bar, nut means for adjustably coupling each of said coupling members to one end of said bar, said fluid motor means being operable to move said bar and each of said sealing means into and out of engagement with said openings, and resilient washer means disposed between said nut means and said bar so that each of said resilient sealing means may be snugly seated against its respective opening.

10. In a laundry appliance having a perforated work treating cylinder mounted for rotation about a horizontal axis, tub means surrounding said cylinder, drain means opening into the bottom of said tub means and having a discharge opening extending for a substantial portion of the length thereof, closure means for said opening including a rigid member and elongate sealing means on said rigid member and being of a size to seal said opening, first and second fluid motor means each including a cylinder and a piston disposed within said cylinder, stem means extending from each of said pistons, and means for adjustably connecting each of said stem means to said rigid member, said fluid motor means being operative to move said sealing means into and out of sealing engagement with said opening.

11. In a laundry appliance having a rotatable perforated work treating cylinder, tub means surrounding said cylinder, drain means opening into said tub means and having a portion substantially tangent to said cylinder and extending in the direction of rotation thereof, said drain means having an opening at the remote end of said portion and extending for a substantial portion of the length of tub means, closure means for said opening including an elongate rigid member at least as large as said opening and disposed in opposed relation relative thereto, elongate sealing means on said rigid member and opposed to said opening, said sealing means being of a size to seal said opening, first and second motive means each including a first part coupled to receive an actuating quantity and a second part operatively associated with said first part and movable in response to said quantity, stem means extending from each of said second parts, and means for adjustably coupling each of said stem means to said rigid member in spaced apart relation, said motive means being operative for moving said rigid member and sealing means into and out of engagement with said opening upon the application of an actuating quantity to said first parts.

12. In a laundry appliance having a perforated work treating cylinder and tub means surrounding said cylinder, drain means opening into said tub means and having an opening extending for a substantial portion of the length thereof, closure means for said opening including an elongate rigid member disposed in opposed relation to said

opening, elongate resilient sealing means affixed to said rigid member in opposed relation to said opening, said sealing means being of the size to seal said opening, a pair of fluid motor means each having a cylinder and a piston, stem means extending from said pistons substantially normal to the axis of said rigid member, adjustment means for adjustably coupling each of said stem means to one end of said rigid member, said fluid motor means being operable to move said rigid member and sealing into and out of engagement with said opening, and resilient means disposed between said adjustment means and said rigid member so that said resilient sealing means may be snugly seated against said opening.
